UNITED STATES PATENT OFFICE.

GEORGE E. WATTS, OF BROOKLYN, NEW YORK.

SHIRT.

1,089,999.

Specification of Letters Patent. Patented Mar. 10, 1914.

Application filed December 10, 1912. Serial No. 736,047.

To all whom it may concern:

Be it known that I, GEORGE E. WATTS, a citizen of the United States, residing at Brooklyn, in the county of Kings and State of New York, have invented new and useful Improvements in Shirts, of which the following is a specification.

This invention relates to shirts, and one of the principal objects of the invention is the provision of simple and efficient means for connecting and disconnecting the forearm portion of the sleeves from the remainder thereof, so that the user may have a full length sleeve with cuffs or a short sleeve for comfort in hot weather.

Another object of the invention is to provide a tuck which conceals the connection between the upper and lower portions of the sleeve and to further provide a draw string or constricting member which holds the lower extremity of the upper portion of the sleeve in engagement with the arm.

Further objects of the invention will appear as the following specific description is read in connection with the accompanying drawing which forms a part of this application, and in which:

Figure 1 is an elevation of a shirt. Fig. 2 is an enlarged detail section taken through one of the sleeves. Fig. 3 is a detail elevation of the upper portion of the sleeve with the lower part disconnected therefrom.

Referring more particularly to the drawings and to Figs. 1 to 3 thereof, 1 represents the body of the shirt which has connected thereto the sleeves consisting each of an upper portion 2 and a lower or forearm portion 3 which is removably connected to the portion 2 as will be hereinafter described.

40 The upper portion of the sleeve has a tuck 4 formed adjacent its end and to the terminal edge of the upper portion is secured an extension 5 having an elastic draw string

6 secured in the hem 7 formed in its lower end. The upper terminal edge of the lower or forearm portion 3 is suitably reinforced and secured to the inner side is a plurality of socket members 8 which coact with the headed studs 9 secured to the terminal edge of the upper portion 2 beneath the tuck 4. 45 When the lower portion of the sleeve is attached to the upper portion the tuck folds over the joint and conceals the connection between the two parts. It will also be seen that when the lower portion of the sleeve is 50 disconnected the headed members of the head and socket fasteners are concealed and the elastic draw string holds the same close to the arm and prevents the same from flapping around.

60 What is claimed is:

1. A shirt sleeve comprising a main part attached to the body of the shirt and having an elastic draw string in its free edge, a lower sleeve, means for removably attaching the lower sleeve to the main part above the terminal end of said main part and means arranged on the main part for concealing the attaching means.

2. A shirt sleeve comprising upper and lower parts, a tuck formed on the upper part adjacent the terminal edge of the upper part, an extension secured to the terminal edge of the upper part and having an elastic draw string in its lower end, and coacting fastening members carried by the lower and upper parts, said tuck adapted to conceal said fastening members and joint between the parts when they are connected.

75 In testimony whereof I affix my signature 80 in presence of two witnesses.

GEORGE E. WATTS.
